UNITED STATES PATENT OFFICE.

WILLIAM A. HUELDONK, OF MERCED FALLS, CALIFORNIA.

CONCENTRATOR.

Application filed August 16, 1926. Serial No. 129,310.

This invention relates to improvements in devices for saving or concentrating precious metals of all kinds, such as gold, silver, platinum, etc.

5 The principal object of my invention is to provide an apparatus of this character especially adapted for separating such metals from the accompanying sand, gravel and the like, by means of a flow of water and vibration, when such metals are in a finely divided condition and are in such minute particles or flakes that ordinary concentrating apparatus can not separate the same from the lighter material generally termed tailings.

10 15 A further object of the invention is to provide a concentrator which can work on mill pulp, and all placer mining material, and the like, without the use of quick silver or other amalgam, and which will operate to save and concentrate sulphides and the precious metals very quickly and separately at one operation, and insuring a very high percentage of concentration of such precious metals and sulphides being obtained.

20 25 A further object of the invention is to provide a simple and inexpensive device and yet one which will be exceedingly effective for the purpose for which it is designed.

These objects I accomplish by means of 30 such structure and relative arrangement of parts as will fully appear by a perusal of the following specification and claims.

In the drawings similar characters of reference indicate corresponding parts in the 35 several views:

Fig. 1 is a side elevation of the complete apparatus.

Fig. 2 is a sectional elevation of the concentrator table and trough unit detached.

40 Fig. 3 is a top plan view of said unit with certain parts broken out.

Fig. 4 is a cross section on the line 4—4 of Fig. 2.

45 Fig. 5 is a longitudinal section of a concentrating attachment to be added as an extension to the main concentrating unit when desired.

50 Referring now more particularly to the characters of reference on the drawings, the numeral 1 denotes a rectangular open topped body in the form of a deep trough of suitable dimensions and construction. This body adjacent its opposite ends has bearing plates 2 whose under edges have an upward 55 and forward slope. These edges ride on longitudinally spaced and transversely extend-

ing rollers 3 supported in a fixed position on a base 4. The member 1 is agitated or shaken longitudinally by means of a longitudinal rod 5 mounted at one end in connection with an eccentric structure 6 which is associated with a fixed transverse shaft 7 mounted above the member 1. This shaft is driven at any desired speed by any suitable form of power plant, which it is not thought necessary to show. The other end of the rod 5 is slideable through a block 8 fixed between supports 9 which are attached to and project upwardly from the sides of the member 1. The rod on both sides of the block has counteracting compression springs 10. These springs are arranged relative to each other and to the block and are of such relative strength or pressure as to cause the member 1 with the reciprocation of the rod to be agitated or shaken with a relatively sharp movement in a longitudinal direction from its forward toward its rear end.

55 The member 1 has a bottom floor or table 11 extending the full length and width thereof. Toward the sides of the member 1 the floor is formed with a plurality of longitudinal riffle grooves 12 extending from end to end of the floor. Between the sets of grooves the floor is formed with a longitudinally extending shallow well 13 terminating short of both ends of the member 1. Projecting upwardly at intervals from the bottom of the well to a point a certain distance above the floor are outlet members 14, while between said members the bottom of the well has other and smaller outlet openings 15 therethrough. Both the openings 14 and 15 discharge into a longitudinal sluiceway 16 mounted in unitary connection with the member 1 and open across the rear end thereof. The floor is flexible and is supported along its center at intervals by vertically adjustable hangers 17 supported by cross beams 18 mounted on top of the member 1. By raising and lowering these rods the floor may therefore be given a transverse, convex, or concave curvature for the purpose hereinafter seen.

60 Extending lengthwise in the member from the forward toward the rear end thereof and from the top downwardly toward the floor are transversely spaced plates 19. These plates extend to and upwardly of the sides of the member 1 for a certain distance and form with said sides, angle bottomed longitudinal troughs 20. The bottoms of said

- troughs are some distance above the floor and the peak or apex is located in a transverse plane adjacent the outermost riffle grooves 12. Cut at longitudinal intervals 5 through the upwardly sloping sides of the plates 19 between the bottom peaks and the adjacent sides of the member 1 are openings 21, while between the sides of the member 1 and plates 19 are longitudinally spaced 10 outlet openings 22, which extend downwardly from the top of the troughs and also discharge onto the floor. Feed chutes 23 carrying the water and material to be worked on discharge into the forward ends of the 15 troughs 20.

Adjacent the rear end of the member 1 the plates 19 make water-tight connection with a downwardly and rearwardly sloping transverse apron 24 which extends the full distance 20 between the sides of the member 1, openings 24^a being cut through the apron to communicate with the troughs 20, said openings being located below the upper ends of outlets 22. At the bottom this apron has a 25 substantially horizontal rearwardly projecting extension 25 which likewise projects the full distance between the sides of the member 1. This extension has a slight downward slope toward its rear end and at such 30 end, which is a short distance from the rear end of the member 1, it terminates a slight distance above the floor 11. The well 13 terminates ahead of said extension. The rear end wall of the member 1 preferably has a 35 rearwardly extending slope toward its upper end as shown. A water pipe 26 by means of which fresh water may be fed into the chamber 27 formed rearwardly of the apron 24, is positioned to discharge water onto the 40 apron 24. The water generally used however is that which passes into the chamber through openings 24^a.

In operation the material with the previous metal particles to be concentrated is discharged 45 into the troughs 20 in connection with a sufficient quantity of water to offset the outflow through the openings 21 and maintain a continual flow lengthwise of the troughs to a certain height therein. The 50 material and water passing through said openings 21 drop onto the floor 11 from which the water, etc. must flow transversely rather than longitudinally owing to the central transverse location of the discharge 55 openings 14 and 15. The material therefore passes transversely of the riffles and the precious metal particles being the heaviest will be caught and retained by such riffles. The tailings fall into the well 13 and pass 60 through the outlets 15 into the sluiceway 16. The openings 15 are so restricted in size relative to the volume of water passing onto the floor as to cause the water on the floor to be maintained at a level thereabove, this 65 level being governed by the height of the

outlets 14 above the floor and through which the excess water overflows into the sluiceway 16. By raising and lowering the floor at the center by adjustment of the hangers 17 it will be seen that the height of the outlets 14 70 relative to the floor at the sides of the member 1 may be altered, so that the depth of water retained on the floor may be varied to suit different conditions.

I have found from actual operation that 75 over 99% of any precious metal particles will be retained in the riffle grooves of this device, so that it is extremely efficient in operation.

With the peculiar longitudinal shaking 80 movement imparted to the apparatus, as previously described, the heavy particles in the riffle grooves are gradually moved along said grooves toward the rear end of the member 1 and finally pass under the apron 85 extension 25 into the chamber 27. The water from the pipe 26 or troughs 20 is fed into said chamber in such quantities as to maintain the water level therein higher than that on the floor ahead of said chamber. 90 This causes a forward current or circulation of water to be set up from the chamber 27, between the extension 25 and the floor 11 to a point ahead of said chamber. This current acts on any comparatively heavy but 95 non-precious particles in the riffles, and in the water, such as sulphides, and carries them forwardly to where they will discharge through the rearmost tailing outlet 15 of the 100 floor well, without disturbing the precious metal particles.

A cover 28 is preferably maintained over said chamber 27 and kept locked until it is desired to remove the contents, which may be done at any time by means of an outlet 105 27^a in the bottom of the chamber, and normally closed from the inside.

If the condition of the material being worked on requires a concentration of the sulphides and the precious metals separate 110 from each other, I may apply an extension member 29 to the rear end of the member 1 (see Fig. 5). This extension has riffle grooves 12^a in the bottom, the same as the grooves 12, a short central well 13^a between the riffles with outlets 14^a and 15^a, a transverse apron structure 24^a beyond the well similar to the apron 24, and an additional water pipe 26^a to discharge onto the apron 24^a. In this case the rear end of the member 1 has side openings 30 to enable the mineral contents still in suspension in chamber 27 to flow onto the side riffles 12^a of the extension. Here they are further acted on by the additional riffles in connection with the flow of water from the pipe 26^a, which acts to separate the precious metals from the heavy sulphides in the same manner as described in connection with the flow of the water from the chamber 27. 130

In this operation, the water level in chamber 27 becomes lowered so that the heavy sulphides pass into the same under the member 25. They then pass through the openings 30 onto the floor 12^a, being then discharged through openings 15^a. The heavy metals in the water pass under the apron 24^a into the chamber beyond the same, which is also kept locked. The sulphides as discharging may be saved, and in any event are separated from the precious metals.

The purpose of the outlets 22 from the troughs 20, in addition to the bottom outlets 21, is to enable water to be discharged onto the floor in the event that said outlets 21 are full of solid material, and will not allow sufficient water to pass onto the floor.

While I have here described one full working unit, such units may be arranged as a battery in side by side relation, to be driven by a single engine and eccentric mechanism.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A concentrator including a main body member, a floor in said member having longitudinally extending riffle grooves therein, a chamber at the rear end of the member and into which the grooves lead, means for discharging water and the material to be treated onto and from said floor in a manner to cause a flow of water and material to take place across the riffles whereby precious metal particles in said material will be caught and deposited in the riffles, means for shaking said member longitudinally to cause said particles to advance along the grooves toward and into the chamber, and means for maintaining a supply of water in the chamber at a level higher than that of the grooves whereby to set up a forward flow of water along the grooves from the

chamber into the member ahead of said chamber.

2. A concentrator including a floor plate having a plurality of longitudinal riffle-grooves therein, a longitudinal depression in the floor to one side of the riffles, outlets from said depression at intervals, and additional outlet members projecting upwardly from said depression at intervals to a point higher than the level of the floor.

3. A concentrator including a floor plate having a plurality of longitudinal riffle-grooves therein, outlets from the floor to one side of the riffles, a feed trough to receive water and the material to be treated extending lengthwise of the floor above the same and to the side thereof opposite the outlets, said trough having discharge openings at intervals in its bottom, and additional outlets discharging onto the floor between said openings and the adjacent side of the floor from a level in the trough higher than that of the first named outlets.

4. A concentrator including a floor plate having a plurality of longitudinal riffle-grooves therein, means for feeding material onto the floor, a chamber at one end of the floor into which the grooves lead, means for causing the material in the grooves to advance to the chamber, means for maintaining water in the chamber, and means acting to cause such water to flow along the grooves and onto the floor ahead of the chamber and against the movement of the material therein toward the chamber.

5. A concentrator including a floor plate having a plurality of longitudinal riffle-grooves therein, means for feeding material onto the floor, a chamber at one end of the floor into which the grooves lead, means for causing the material in the grooves to advance to the chamber, means for maintaining water in the chamber at a predetermined level, and a substantially horizontal apron projecting into the chamber from the forward end thereof and disposed across and adjacent the floor with a slight upward slope from its rear end.

In testimony whereof I affix my signature.
WILLIAM A. HUELDONK.
